(57) **CLAIM**

The ornamental design for a board game, as shown and described.

DESCRIPTION

FIG. 1 is a front, right, and top perspective view of a board game, showing my new design;

FIG. 2 is a rear, left, and bottom perspective thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a detailed view taken from encircled portion labeled "9" in FIG. 1; and,

FIG. 10 is another perspective view thereof.

The short-dash and long-dash broken lines and the number 9 in FIGS. 1 and 9 denote the boundaries of the detail areas and form no part of the claimed design. The even broken lines in the drawings depict portions of the board game that form no part of the claimed design.
